COMBINED SERVING TRAY AND GLASS HOLDER

Benjamin K. Milbourne, 319 Winchester Road, San Jose, Calif., and Theodore C. Bayless, 20160 Cherry Lane, Saratoga, Calif.

Filed July 3, 1963, Ser. No. 75,647

Term of patent 14 years

(Cl. D44—10)

We claim:

The ornamental design for a combined serving tray and glass holder, as shown.
